UNITED STATES PATENT OFFICE.

FELIX WAJTUKIEWICZ, OF NEW YORK, N. Y.

DAVENPORT-BED.

1,360,478.

Specification of Letters Patent. Patented Nov. 30, 1920.

Application filed September 15, 1919. Serial No. 323,758.

To all whom it may concern:

Be it known that I, FELIX WAJTUKIEWICZ, a citizen of the United States, residing at New York, in the county of New York and 5 State of New York, have invented new and useful Improvements in Davenport-Beds, of which the following is a specification.

This invention relates to a combined davenport and bed and aims to provide a 10 neat and attractive article of furniture, which is capable of being folded to form a neatly upholstered davenport or settee and which may be easily and quickly converted into a comfortable bed.

15 Another object of the invention is the provision of an article of furniture of this character, in which the back and seat are of separate formation and are connected together by levers of novel formation which, 20 when the davenport is open, will cause the back to turn and assume a position substantially flush with and parallel to the seat, so as to provide separate and distinct mattresses arranged side by side.

25 Another object is the provision of a combined davenport and bed in which the bed clothes may be folded out of sight when used as a davenport without the necessity of their removal, thus leaving them in 30 convenient position for use when the invention is converted into a bed.

Other objects and advantages of the invention will appear as the following description is read in connection with the accompanying drawings.

In the drawings:

Figure 1 is a perspective view showing the invention arranged as a davenport.

Fig. 2 is a similar view arranged as a bed.

40 Fig. 3 is a central transverse section with the invention shown in the position illustrated in Fig. 1.

Fig. 4 is a similar view, a section being taken just inside of one of the end members 45 of the frame and showing the operating levers in the position assumed when closed as a davenport.

Fig. 5 is a similar view, showing the davenport partly open preparatory to converting 50 the same into a bed.

Fig. 6 is a like view fully open.

Fig. 7 is a transverse sectional view showing the seat in raised position, the section being taken on a line with the means for 55 supporting the seat in this position.

Fig. 8 is a detail longitudinal section taken through one end of the seat and frame.

Fig. 9 is a detail horizontal section taken on a line above the lower connecting bars of the frame.

60

Fig. 10 is a fragmentary perspective view of one end of the seat frame or base, showing the brackets secured thereto.

Fig. 11 is a fragmentary perspective view of the lower inner face of one of the end 65 members showing the brackets carried thereby.

Referring to the drawings in detail, wherein like characters of reference denote corresponding parts, the invention includes 70 a frame which is formed of end members 10, which are connected together by lower spaced connecting bars 11 and a top connecting bar 12. The lower connecting bars 11 are connected by transverse end bars 13, 75 the space between these bars being closed, as at 14, to provide a base or bottom for the seat of the davenport, as will be apparent, and to provide a compartment 15 for the reception of pillows, or extra blankets or bed 80 clothes.

The seat of the davenport, which is indicated at 16, is formed of a frame 17, the latter supporting spaced transverse bars 18, to provide supports or springs 19, upon 85 which rests the seat 16. This seat is suitably upholstered and is adapted to form both a seat used as a davenport and a mattress used as a bed.

The back, which is indicated at 20, is constructed similarly to the seat and includes a frame 21 and spaced transverse bars 22, which support springs 23, upon which the upholstery of the back 20 rests.

The seat 16 has its frame 17 hingedly or 95 pivotally secured to the rear of the frame formed by the connecting bars 11 and the transverse end bars 13, as indicated at 24. This seat thus forms a cover for the compartment 15, which may be held in raised 100 position, when desired, by means of levers 25. One end of each of these levers is pivotally connected near the front edge of the frame 17, their opposite ends being curved and notched, as indicated at 26. These 105

notches are adapted to engage pins 27 positioned transversely of a slot or groove 28 provided in each of the transverse end bars 13. This provides convenient means for obtaining access to the interior of the compartment 110

ment 15, when desired. To hold the seat down against the front connecting bar 11, there is provided a bolt 29, which is slidably mounted upon the bottom of the seat for engagement with a keeper plate carried by the front connecting bar 11.

The seat is detachably connected to the end members 10, by detachably securing the frame or base formed by the bars 11 and 13 10 to the said end members. For this purpose there is secured at each end of both the transverse end bars 13 and the end members 10, an apertured L shaped bracket 31, the brackets secured to the end members 10 15 being disposed at right angles to the other brackets. These brackets are positioned for detachable engagement with studs 32, which are carried by brackets 33 also secured to the end members and to this frame. Pivotally secured to each of the end members 10, is a latch 34, which is adapted to engage the upper edge of the front connecting bar 11, so as to prevent upward movement of this bar and consequently disengagement of the 20 studs from the apertured bracket 31.

Pivottally connected to each end of the back 20, near the upper edge thereof, as shown at 35, is one end of a substantially L shaped lever 36. The opposite end of this 30 lever is pivotally connected, as indicated at 37, to the end member 10. Pivottally connected to each end of the back 20, near the opposite or lower end thereof, as indicated at 38, is one end of a substantially U shaped 35 member 39, the said end being extended to provide a leg 40 at each end of the back when the invention is used as a bed. The opposite end of the lever 39 has its extremity pivotally secured to the end member 10. By this arrangement of levers when the 40 invention is changed from a davenport to a bed, the seat 16 will remain in position, while the back 20 will be moved forward and completely rotated, so that when it reaches a position parallel to and flush with the seat, the upholstered portion of the back 45 will be uppermost to provide a mattress. Thus two separate and distinct mattresses are provided, which in effect form a divided 50 double twin bed. The ends of the levers which are pivoted to the end members are positioned between parallel plates or bars 42, while the ends which are connected to the back are pivoted upon wear plates or 55 bars 43, thereby keeping the levers in proper alignment and preventing wear upon the frames of both the seat and back.

Hingedly secured to the top connecting bar 12, is a strip 44, which is adapted to 60 fold down over the upper edge of the back to provide a finish, which may be lifted to permit proper movement of the back when changing from a davenport to a bed. To facilitate this movement, there is provided a

tab 45, secured to the upper edge of the 65 back.

Secured along the front edge of the seat, as indicated at 46, is one edge of a strip of fabric 47, the opposite edge of this strip being secured to the lower edge of the back. 70 When folded for use as a davenport, the strip of fabric 47 provides a cover for the seat, so that the bed clothes may be folded upon the seat and hidden from view when the bed is not in use. Any suitable means 75 may be provided for securing the edge of the strip 47 to the back, but it is preferred to secure along the rear lower edge of the back, a rod 48, which is held in suitable brackets 49. The adjacent edge of the strip of fabric 80 47 is provided with tabs 50, which may be tied around the rod 48 in the form of loops and provide for removably securing this edge of the strip 47 in position.

Secured in brackets 51, positioned along 85 the rear edge of the seat 16 is a rod 52, which is designed for the purpose of providing means for securing one edge of a sheet 53, or other article of bed wear. This latter is provided with a hem along its edge 90 for the reception of a rod 54, around which are secured tabs 55, which may be formed into loops around the rod 52. When in use as a davenport, this sheet may be folded centrally upon the seat and will be covered 95 by the strip of fabric 47, which also covers a spread or other bed clothes.

The rear of the frame may be provided 100 with a curtain 56, which is supported upon a rod 57 mounted in brackets 58, depending from the top connecting bar 12.

It is believed that when the foregoing 105 description is read in connection with the accompanying drawings, the construction, operation and advantages of the invention will be apparent. The right is reserved to make such changes as properly fall within the scope of the appended claims.

Having described the invention what is 110 claimed is:

1. A combined davenport and bed, comprising a frame including end members, an upholstered seat, a base for supporting the seat, an upholstered back, means for pivotally securing the back to the frame, whereby 115 the latter will be caused to assume a position parallel to the former when the bed is open and means including apertured L-shaped brackets and offset engaging lugs carried by the end members and base to secure the latter in position.

2. The combination with a combined 120 davenport and bed, of a longitudinally disposed rod secured along the lower edge of the back and the rear edge of the seat to provide bed clothes securing means.

In testimony whereof I affix my signature.
FELIX WAJTUKIEWICZ.
